CLAIM

The ornamental design for a motorcycle fender, as shown and described.

DESCRIPTION

FIG. 1 is a right side elevational view of the motorcycle fender as it would be mounted on a motorcycle showing my new design with the broken lines of the motorcycle being shown for illustration purposes only;

FIG. 2 is an enlarged perspective view thereof;

FIG. 3 is an enlarged right side elevational view thereof;

FIG. 4 is an enlarged front elevational view thereof;

FIG. 5 is an enlarged left side elevational view thereof;

FIG. 6 is an enlarged rear elevational view thereof;

FIG. 7 is an enlarged top plan view thereof; and,

FIG. 8 is an enlarged bottom plan view thereof.
